UNITED STATES PATENT OFFICE.

ANDREW W. WELSH AND WALTER SHECK, OF PHILADELPHIA, PENNSYLVANIA.

ROTARY ENGINE.

No. 892,201.

Specification of Letters Patent. Patented June 30, 1908.

Application filed June 18, 1907. Serial No. 379,675.

To all whom it may concern:

Be it known that we, ANDREW W. WELSH and WALTER SHECK, citizens of the United States, residing at Philadelphia, in the county of Philadelphia and State of Pennsylvania, have invented certain new and useful Improvements in Rotary Engines, of which the following is a specification, reference being had therein to the accompanying drawing.

This invention relates to an improved rotary engine, and has for its object the improvement of the construction of valve means employed in the construction of a complete engine.

Another object of the invention is the provision of means for facilitating the drawing into an engine a charge of gas, compressing, and subsequently, igniting the gas for rotat-

ing a piston.

With these and other objects in view, the invention consists of certain novel constructions, combinations, and arrangements of parts, as will be hereinafter fully described and claimed.

In the drawings: Figure 1 is a longitudinal, vertical sectional view of an engine constructed in accordance with the present invention. Fig. 2 is a transverse, vertical, sectional view of the engine depicted in Fig. 1. Fig. 3 is a top plan view of the structure depicted in Fig. 1. Fig. 4 is a plan view of our valve, showing the same supported upon the casing of the engine. Fig. 5 is a longitudinal, vertical, sectional view of another embodiment of our rotary engine employing our valve in the construction thereof.

Referring to the drawings by numerals, 1 designates the casing, which is carried by base 2. Preferably near the top of the casing 1, there is a primary valve compartment 3, while, preferably, upon the side of the casing 1, there is formed an auxiliary valve compartment 4. A piston 5 is fixedly secured, by any suitable fastening means, to, preferably, a horizontal shaft 6. The piston 5 is positioned within the casing 1, and as said shaft 6 is journaled upon the sides of said casing, the piston 5 may be rotated freely within the casing. The piston 5 is provided with a cam portion 7, which cam portion 7 is provided, at 8, with a gradually curved or convexed surface, while upon the opposite side, the piston is provided with a straight edge or surface 9, whereby movement of the valve 10 will be more freely permitted.

The valve 10 is positioned within the primary valve compartment 3, and is capable of having a rotary movement therein. The valve 10 comprises a semi-cylindrical shell 60 provided with a hollow body and with a lower concaved or rounded face 11, which register with the inner face of the casing 1, when the outer edge or face 12 of the cam portion 7 of the piston is passing the valve. 65 The valve 10 is provided with an upper, enlarged opening 13, and with an auxiliary opening or discharge port 14. By reason of the enlarged opening 13, when the valve 10 is entirely within the valve compartment 3, 70 the interior of the hollow body of the valve is in communication with the inlet port 15, which port 15 communicates with, preferably, a curved pipe 16 and port 17 of the casing. Gas discharged into the portion 18 75 formed between the casing 1 and the piston 7, will be permitted to pass through port 17 pipe 16 and port 15 into the hollow valve 10, when the primary opening 13 of said valve registers with port 15.

A valve 19 is rotatably mounted within the auxiliary valve compartment 4, and said valve 19 is provided with a passage or channel 20, whereby gas discharged from a suitable carburetor or vaporizer through pipe 21 85 may also be discharged through port 20 into the portion 18 of the casing 1 when the valve 19 has its passage 20 communicating with said pipe 21. The valve 19 is provided with a lower, inwardly curved or concaved piston-engaging surface 22, similar to the surface 11 of valve 10. A suitable discharge outlet 23 is formed upon the casing 1, preferably contiguous to the inlet valve 19, whereby after the cam portion 7 of the piston 5 has passed 90 the discharge opening 23, the burned gases will be discharged through said discharge opening 23. An aperture 24 is formed, preferably, in a vertical plane upon the outwardly bulged portion of the casing in which 95 the primary valve compartment 3 is formed, and threaded into the aperture or opening 24 is an ordinary spark plug 25 of the jump-spark type.

It is desirable to have the ends 26 of the 105 rotatable valves 10 and 19 normally in engagement with the piston 5, and, therefore, to accomplish this result, we have extended one of the journals 27 of each valve member beyond the outside of the casing 1, and 110 mounted upon this journal or stub shaft 27, is, preferably, a coil spring 28. The inner

end of the coil spring 28 is seated, at 29, in a socket formed in boss 30 of the casing 1 (Fig. 4), and the outer end of the spring is seated in a socket 31 formed in a collar 32, 5 which collar is, preferably, threaded upon the journal or stub shaft 27. A locking-nut 33 is threaded upon the outer end of the journal or stub shaft 27 against the adjusting-collar 32. It will be noted that by rotating 10 the collar 32 in one direction, the tension of the spring may be increased, and by reason of the locking-nut 33, the collar can be prevented from working loose. The springs 28 will, at all times, exert sufficient 15 pressure upon the valves to hold them in the position shown in Fig. 1, and while the piston may rotate the valves within their compartments, still the tension of the springs is sufficient to rotate the valves to a position for 20 preventing back pressure of gases in the casing 1.

In Fig. 5, we have shown our improved valve applied to a steam engine. In this embodiment, the outwardly-bulged portion 25 of casing 1 in which the valve compartment 3 is formed, is provided with an inlet port or opening 15', which communicates with a valved supply pipe 16'. It will be obvious 30 that not only steam may be supplied to this compartment, but also compressed air or liquid. The casing is provided with a suitable discharge opening 23', preferably contiguous to the valve compartment 3, so that the full benefit of the pressure of the steam or 35 liquid upon the cam portion of the rotary piston may be secured before the liquid is exhausted or discharged from the casing.

If the piston is in the position shown in Fig. 1, the compressed charge of gas in the 40 hollow valve 10 will be discharged against the cam portion 7 of the piston, and synchronously with the discharge of gas, caused by the lower end 26 of the valve 10 dropping against face 9, the gas will be ignited by 45 means of the spark plug 25. Synchronous with the ignition of the charge of gas, a new charge 7 is being supplied to portion 18 of the chamber within the casing, and as the piston rotates and the cam portion 7 comes 50 in engagement with the auxiliary valve 19, the same will be swung upon its journals and the passage 20 closed, and as the cam portion 7 passes this valve 19, the same will fall into the position illustrated in Fig. 1. It will be 55 noted that the passing of the cam portion 7 by the valve 19 will cause the fresh charge of gas to be compressed, and owing to the comparatively curved face 8 of the cam portion, the valve 10 will be gradually rotated and 60 the port 15 placed in communication with the interior of said hollow valve, whereby the fresh charge will be forced into said valve preparatory to being discharged behind the cam portion of the piston. Owing 65 to the peculiar structure of the cam portion

of the piston, as the same passes the valve 19, it will also suck or draw in a new charge of gas, and, therefore, it will be noted that we have provided a simple means for drawing into an engine a charge of gas, compressing the same, and subsequently, discharging and synchronously igniting the compressed charge behind the cam portion or wing of a rotary piston.

In the embodiment illustrated in Fig. 5, 75 the operation of our valve 10 is substantially the same as in Fig. 1. As the cam portion 7 is passing the valve 10, the interior or hollow portion of the valve is being filled by live steam, which steam is, subsequently, 80 discharged behind the cam portion as the same passes beyond the valve and permits the lower end 26 to swing into engagement with the straight face 9; the straight face 9 of the piston permitting a more even "drop", 85 or freer movement of the valve. Immediately prior to the receiving of a new charge of steam against the piston, the dead steam is discharged through the outlet 23.

What we claim is:

1. In a rotary engine, the combination with a casing, a piston journaled in said casing, of a valve positioned upon said casing and being capable of rotary movement, means carried by said piston for moving said valve, a boss formed upon said casing, a stub shaft secured to said valve and journaled in said boss, said stub shaft extending beyond the outer face of said boss, a coil spring positioned upon the extended end of said stub shaft, the inner end of said spring seated within a portion of said boss, an adjusting collar carried by said shaft, the outer end of said spring seated within said collar, and means carried by said stub shaft for locking 95 said collar in an adjusted position upon said stub shaft, said casing provided with an inlet opening being capable of communicating with said valve, and said casing provided with a discharge opening.

2. In a rotary explosive engine, the combination with a casing, of a piston mounted within said casing, a rotatable valve carried by said casing, means carried by said piston and being capable of rotating said valve, said valve provided with a hollow body and with a plurality of openings or ports, one of said openings larger than the other opening, said casing provided with a spark plug contiguous to said valve, said spark plug being capable 105 of igniting gases within said valve, means for supplying gases under pressure to said valve, and said casing provided with a discharge opening.

3. In a rotary engine, the combination 115 with a casing, of a rotatable piston provided with a cam portion mounted within said casing, said casing provided with a valve compartment and with an opening leading from said valve compartment, a spark plug 120

threaded into said opening, said casing provided with a plurality of openings or ports contiguous to said valve compartment, a single pipe positioned outside of said casing 5 and connecting said ports, a semi-cylindrical valve journaled in said valve compartment, said valve provided with a hollow body and with a large and a small opening or port, the interior of said valve in communication at all 10 times with the spark plug, means for normally preventing the ports upon the casing from communicating with the interior of said valve, means for supplying a charge of gas to said ports and pipe, whereby when said valve is rotated by the cam portion of said piston, 15 said charge of gas can enter the hollow body of said valve, and said casing provided with a discharge opening.

4. In a rotary explosive engine, the combination with a casing, of a rotary piston positioned within said casing, a pair of semi-cylindrical valves journaled upon said casing, said valves normally in engagement near one end with said piston, and thereby preventing 25 back pressure of gases within said casing, means carried by said piston and adapted to move said valves upon said casing, means for normally supplying a charge of gas to one of said valves, and means adapted to supply a 30 charge of gas under pressure to the other valve, means for igniting the compressed charge of said gas within said valve, and said casing provided with a discharge opening.

5. In a rotary explosive engine, the combination with a casing, of a rotary piston mounted within said casing, a pair of rotatable valves journaled upon said casing, said piston provided with means for rotating said valves, each valve provided with means for 35 permitting a charge of gas to pass therethrough, means for supplying a charge of gas under pressure of one of said valves, a spark plug normally in communication at all times with one of said valves; whereby a charge of 40 gas under pressure within said valve may be ignited, and said casing provided with a discharge opening.

6. In a rotary explosive engine, the combination with a casing, of a piston mounted 50 within said casing, a hollow valve carried by said casing, means carried by said piston for moving said valve, a spark plug mounted upon said casing and normally in communication with the interior of said valve, means

for supplying gases under pressure to said 55 valve, and said casing provided with a discharge opening.

7. In a rotary engine, the combination with a casing, a piston mounted within said casing, of a hollow, rotatable valve mounted 60 upon said casing, said valve provided with a large opening or port and with a small opening or port, said valve provided with a stub shaft extending beyond one side of said casing, a collar mounted upon said stub shaft, 65 a spring fixedly secured at one end to said collar and fixedly secured at its opposite end to said casing, and means carried by said stub shaft for adjusting said collar for controlling the tension of said spring. 70

8. In a rotary engine, the combination with a casing, of a rotary piston, provided with a cam portion, mounted within said casing, a rotatable valve mounted within said casing and adapted to normally engage said 75 piston, said valve provided with a plurality of ports and with a hollow body, said casing provided with means for conducting compressed gases from in front of the cam-portion to one of the ports of said valves and 80 permitting the gases to be discharged into the body of said valve and, subsequently, behind the cam-portion of said piston, and said casing provided with means for igniting the gases behind the cam-portion of said 85 piston.

9. In a rotary engine, the combination with a casing, a rotatable piston provided with a cam-portion, mounted in said casing, of a hollow valve rotatably mounted in said 90 casing, said valve provided with a plurality of openings or ports, said casing provided with means forming a passage for permitting the passage of gases from the casing through one of the ports of the valve and allowing 95 said gases to be discharged into the body of said valve, said cam-portion of the piston being adapted to move said valve upon said casing, and means for igniting the gases in 100 said valve.

In testimony whereof we hereunto affix our signatures in presence of two witnesses.

ANDREW W. WELSH.
WALTER SHECK.
